UNITED STATES PATENT OFFICE.

MAY R. SMITH, OF BROOKLYN, NEW YORK.

TOILET-CASE.

1,218,222.

Specification of Letters Patent.

Patented Mar. 6, 1917.

Application filed March 27, 1914. Serial No. 827,692.

To all whom it may concern:

Be it known that I, MAY R. SMITH, citizen of the United States of America, and a resident of the borough of Brooklyn, county 5 of Kings, city and State of New York, have invented certain new and useful Improvements in Toilet-Cases, of which the following is a specification.

This invention relates to toilet cases, and 10 comprises a box or case of compact and attractive form, and susceptible of ornamentation to a high degree if desired, said box or case having compartments for face powder and a powder puff or the like, and for several 15 spools of thread, a needle case, a pin cushion, a thimble and other articles. An inner flap or cover of the box is also provided with a mirror.

My invention consists in the novel features of construction and arrangement hereinafter specified and particularly pointed out in the appended claims.

The object of my invention is to provide a very simple and compact toilet case of the 20 type referred to, which shall have minimum dimensions and weight for the desired purpose.

I will now proceed to describe my invention with reference to the accompanying 25 drawings, and will then point out the novel features in claims. In the said drawings:

Figure 1 shows a top view of one form of my improved toilet case, closed; Fig. 2 shows a top view of such form of toilet case, open; 30 Fig. 3 shows a transverse section of said toilet case, and Fig. 4 a longitudinal section thereof. Fig. 5 shows a top view of an alternative form of toilet case, open; and Fig. 6 shows a transverse section of such 35 alternative form.

Referring first to Figs. 1-4 inclusive. The case comprises a top 1 and a bottom 2, hinged together at 3, and forming, when closed, an ovoid body; though this form, 40 while convenient for the purpose, and extremely compact, is not positively essential. The two halves, 1 and 2, of the box, are preferably of similar form and of approximately equal dimensions. The top one is provided with a curved partition 4 and a hinged flap 5 which together divide off, in the interior of the box, a compartment 6 adapted to receive face powder and powder puff, or a piece of cloth having face powder upon it; 50 and the hinged flap 5 (the axis of the hinge of which is longitudinal in the form shown),

preferably has a mirror surface 7 which will be exposed when the flap 5 is thrown backward, as indicated particularly in Fig. 2.

In the bottom member 2 of the box, there 60 is a hollow spindle 8, preferably screw connected at its base to a pin 9 hinged at 10 to the bottom 2 of the box. This spindle 8, being hinged to the bottom 2 of the box, may be swung up out of such bottom 2, 65 whenever desired; and yet is held from accidental detachment from the structure, by its screw connection to the pin 9; though such spindle may be unscrewed from the pin whenever desired. Upon this spindle 8 70 are mounted, loosely, a number of spools 11 which may carry thread of different types, or colors, or sizes. At its outer end, the spindle 8 is provided with spring clips 12, adapted to engage and hold detachably a 75 thimble 13. The thimble clips 12 prevent removal of the spools 11 from the outer end of the spindle 8, and the box-member 2, itself, normally prevents such spools from sliding off the lower end of said spindle; 80 though when it is desired to remove or replace one of these spools, it is a simple matter to unscrew the spindle 8 from the pin 9, whereupon the spindle, with the spools on it, may be lifted out of the box, and the 85 spools removed and replaced.

The spindle 8 is hollow, as previously stated, and within it is located a removable tubular needle case 14 which, in the construction shown, has a plurality of needle 90 compartments 15 closed at the end by a rotatable cap 16 having within it an orifice 17 which may be brought into registry with any one of the needle compartments 15 by rotation of the cap. This needle case is surrounded externally by a pin cushion 18, the pin cushion being of such thickness that it will fit readily within this spindle 8. I have shown this pin cushion as holding a plurality of pins 19. In the construction shown in Figs. 1-4 inclusive, the pin 9 is located somewhat to one side of the longitudinal axis of the box, and is so located that the full depth of the top and bottom of the box are available for the reception of the thimble 13; the thimble lying as shown particularly in Fig. 3, to one side of the compartment 6. In other words, the necessary diameter of the thimble 13 determines the thickness of the box, which box is preferably made as thin as it may be and yet provide space for the reception of the thimble. 100 105 110

The spaces alongside of the thimble 13 and the spools 11 form convenient receptacles for various toilet articles, such for example, as scissors, a knife, etc.; none of which articles are shown, as they form no part of the structure.

In the alternative structure shown in Figs. 5 and 6, the powder compartment, here designated by numeral 6^a, is located centrally within the top 1, the cover 5^a for this compartment being hinged at one end. In this form a space is provided between the flap 5^a and the bottom of the box for the reception of the thimble, and therefore the toilet case shown in Figs. 5 and 6 is somewhat thicker than that shown in Figs. 1-4 inclusive, but, also, is somewhat more capacious.

What I claim is:—

- 20 1. A toilet case such as described, comprising a box having a top and bottom, both of which are recessed internally, one of said recessed members provided with an internal compartment occupying a portion only of the width of that member and with a movable cover for that compartment, and a combined thread and thimble holder secured within the other member of said box and to one side of said internal compartment and occupying not only a portion of the recess of the member within which such combined thread and thimble holder is secured, but also a portion of the recess of the other member.
- 35 2. A toilet case such as described comprising a box having top and bottom both of which are recessed internally, one of said recessed members provided with an internal compartment occupying a portion only of the width of that member, and with a movable cover for that compartment, and a thread holder secured within the other member of said box and to one side of said internal

compartment and occupying not only a portion of the recess of the member within which such combined thread and thimble holder is secured, but also a portion of the recess of the other member, to one side of the compartment of that other member.

3. A toilet case such as described, comprising a top and bottom, both of which are recessed internally, one of said recessed members provided with an internal compartment occupying a portion only of the width of that member, and with a movable cover, for that compartment, and a thimble holder located within the case and to one side of said internal compartment and occupying not only a portion of the recess of the member within which such combined thread and thimble holder is secured, but also a portion of the recess of the other member, to one side of the compartment of that other member.

4. A toilet case such as described, having a top and bottom, the former adapted to open with respect to the bottom, a thread carrier within said case, and a pin, hinged to one member of said case to which said thread carrier is screw threaded.

5. A toilet case such as described, having a top and bottom, the former adapted to open with respect to the bottom, a thread carrier within said case, and a pin, hinged to one member of said case to which said thread carrier is screw threaded, said thread carrier having near one end, thimble-holding means which serves to retain spools in place upon said thread carrier.

In testimony whereof I have signed this specification in the presence of two subscribing witnesses.

MAY R. SMITH.
